W. W. IDLE.
WIRE STRETCHER.
APPLICATION FILED MAR. 4, 1916.

Patented Feb. 13, 1917.

Inventor

WALTER W. IDLE

By Watson E. Coleman

Attorney

UNITED STATES PATENT OFFICE

WALTER W. IDLE, OF URBANA, OHIO.

WIRE-STRETCHER.

1,216,233.

Specification of Letters Patent. Patented Feb. 13, 1917.

Application filed March 4, 1916. Serial No. 82,199.

To all whom it may concern:

Be it known that I, WALTER W. IDLE, a citizen of the United States, residing at Urbana, in the county of Champaign and State of Ohio, have invented certain new and useful Improvements in Wire-Stretchers, of which the following is a specification, reference being had to the accompanying drawings.

10 This invention relates to an improved wire stretcher, and has for its primary object to provide a very simple and easily operated means for stretching a fence wire.

It is a more particular object of the invention to provide a device for the above purpose, including means for clamping the device upon a fence post, a slidably mounted support, wire clamping means arranged upon said support, and manually operable 20 means for shifting the support and thereby stretching the wire.

It is an additional object of the invention to provide operating means for the shiftable wire clamp, which includes an oscillatable lever, and means for moving said clamp in the same direction in the oscillating movement of the lever in either direction whereby the wire may be quickly stretched.

It is still another object of the invention 30 to provide a wire stretching means which is simple and durable in its construction, may be operated with a minimum of manual labor, and is capable of manufacture at relatively small cost.

35 With the above and other objects in view, my invention consists in the novel features of construction, combination and arrangement of parts to be hereinafter more fully described, claimed and illustrated in the accompanying drawing, in which,

Figure 1 is a plan view of my improved wire stretcher showing the same as applied in operative position to a fence post;

Fig. 2 is a side elevation thereof;

45 Fig. 3 is a section taken on the line 3—3 of Fig. 2;

Fig. 4 is a section taken on the line 4—4 of Fig. 2; and

Fig. 5 is a horizontal section showing the 50 means for actuating the movable clamping jaw.

Referring in detail to the drawing, 5 designates the cylindrical body bar or rod which is provided upon one end with the 55 integral, laterally extending, spaced plates 6, and a longitudinally projecting, curved

jaw 7 extending from the end of the rod 5 beyond said plates. Between the spaced plates 6, a movable clamping jaw 8 is mounted upon the pivot pin 9. This jaw is provided with a shank portion extending between the plates, which has a series of cog teeth 10 formed upon its end. A lever 11 is also pivotally mounted at one end, as at 12, between the plates 6 and is similarly 65 formed with a series of cog teeth 13 meshing with the teeth 10 of the movable clamping jaw. The jaws 7 and 8 are adapted to be disposed upon opposite sides of a cylindrical steel corner post such as is now commonly 70 used in the erection of wire fences, and when the lever 11 is forced inwardly toward the cylindrical body bar 5, the jaw 8 is also moved inwardly toward the fixed jaw 7 and into clamping engagement upon the post. 75 An elongated link, indicated at 14, is pivotally connected to the end of the lever 11 and is adapted to be swung over the end of the rod 5 so as to hold the lever against 80 movement and retain the jaw 8 in its clamping position.

Upon the cylindrical rod 5, the sliding support 15 is mounted, said support including spaced parallel bars 16 disposed upon opposite sides of the rod 5 and in spaced 85 relation thereto. One end of this support is formed with an angularly disposed lug 17, and adjacent to this lug the clamping cam 19 is pivoted, as indicated at 20. In the edge of this cam member, gripping teeth 90 20' are formed and are adapted to bite into a fence wire arranged between the cam and the lug 17. In this manner, it will be apparent that the wire to be stretched may be very easily and quickly connected to the 95 sliding support.

The arms 22 of a forked lever 21 straddle the cylindrical rod 5 and extend between the bars 16 of the support 15. These arms are mounted upon the pivot pins or screws 23 100 centrally secured in the respective bars 16 of the support. Upon each side of the forked lever, a ring or annulus 24 is loosely engaged upon the rod 5, and to each of these rings links 25 and 26 respectively, are pivotally connected at one of their ends. The other ends of these links are pivotally held between the arms of the forked lever upon relatively opposite sides of the rod 5. A coil spring 27 is loosely engaged upon the 110 rod 5 between one of the rings 24 and the lever 21, and a similar spring 28 is disposed

between the other of the rings 24 and the end of the sliding support 15. The ring 24 first referred to is provided with a lateral extension or finger piece which may be engaged and actuated to release the gripping engagement of said ring upon the rod, whereby the sliding support may be shifted inwardly upon the rod 5.

In the operation of the device, the same is first clamped upon the fence post in the manner above referred to, and the end of the wire is then securely clamped to the movable support 15 by means of the cam member 19. The operator now oscillates the lever 21. In the movement of this lever in one direction, the link 26 will serve as the fulcrum, the ring to which said link is connected having frictional biting engagement upon the rod and remaining stationary thereon while the other of the rings will slide upon the rod with the support. When the movement of the lever is reversed, the other link 26 becomes the fulcrum for the lever, and the support and the ring or annulus 24 which was formerly stationary is shifted upon the rod 5 in the same direction as formerly. Thus, the movement of the sliding support progresses outwardly toward the end of the rod, such movement being limited by a stop pin or key indicated at 30, which is inserted through an opening in the end of the rod 5. The finger piece 29 may now be pressed inwardly toward the operating lever and said lever, together with the support, again shifted inwardly upon the rod and positioned for the attachment of another fence wire, when the operation above described may be repeated.

From the above description, taken in connection with the accompanying drawing, the construction, manner of operation and several advantages of my invention will be clearly and fully understood. The support provided with the clamping means for the wire may be turned upon the rod 5 and disposed in the most convenient position for the manipulation of the lever 21. The simple construction of the device renders the same highly durable in practical use and capable of easy and quick application or transportation from place to place.

Copies of this patent may be obtained for five cents each, by addressing the "Commissioner of Patents, Washington, D. C."

While I have shown and described the preferred construction and arrangement of the several elements, it is, of course, to be understood that the same is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

1. A wire stretcher including a supporting rod and means for clamping the rod to a fence post, a slide member mounted on the rod having parallel portions disposed on opposite sides of the rod and integrally connected at their ends, an operating lever pivotally mounted between the parallel portions of the slide member, rings engaged upon the rod on relatively opposite sides of the lever and adapted to frictionally engage said rod, links pivotally connected to the rings and to said lever upon relatively opposite sides of its pivot, and wire clamping means carried by the slide member.

2. A wire stretcher including a supporting rod provided with means for clamping the same to a fence post, a slide member on said rod having parallel portions extending longitudinally on opposite sides of the rod, an operating lever pivotally mounted between the parallel portions of the slide member, rings engaged upon the rod on relatively opposite sides of the lever and at approximately equal distances therefrom, links connecting the rings to the lever on relatively opposite sides of its pivot, a spring disposed between one of the rings and the lever and a second spring disposed between the other lever and one end of the slide member, said springs yieldingly holding the rings in frictional engagement with the rod, and wire clamping means on one end of said slide member.

In testimony whereof I hereunto affix my signature in the presence of two witnesses.

WALTER W. IDLE.
